UNITED STATES PATENT OFFICE.

ANDREW CAMPBELL, ANDREW C. CAMPBELL, AND CHARLES H. CAMPBELL,
OF BROOKLYN, NEW YORK, ASSIGNEES TO CAMPBELL PRINTING PRESS
AND MANUFACTURING COMPANY.

CYLINDER PRINTING-PRESS.

SPECIFICATION forming part of Letters Patent No. 259,478, dated June 13, 1882.

Application filed April 8, 1881. (No model)

To all whom it may concern:

Be it known that we, ANDREW CAMPBELL,
ANDREW C. CAMPBELL, and CHARLES H.
CAMPBELL, citizens of the United States, re-
siding at Brooklyn, in the county of Kings
and State of New York, have invented a new
and useful Improvement in Cylinder Printing-
Presses, of which the following is a specifica-
tion.

This invention relates to that class of print-
ing-presses in which the cylinder makes two
revolutions on its axis to each evolution of the
press. In such machines the cylinder neces-
sarily has two distinct motions—first, the uni-
form revolutions on its axis, and, secondly,
the alternate rise and fall of said axis at fixed
intervals during each evolution of the press.
To obtain these motions, and thereby secure
desirable results, various well-known devices
are now employed, though in all such machines
the bed and cylinder are kept in perfect uni-
formity of motion through the medium of gear-
wheels. When the bed and cylinder are in
contact, as at the time of giving the impres-
sion, said cylinder is down, and in this position
the teeth of the cylinder-gear are properly in
“mesh” with those of the pinion below it, and
through which motion is communicated to the
bed; but when the cylinder lifts to permit
the bed to return preparatory to giving the
succeeding impression the cylinder-gear and
pinion are not properly in mesh, because no
means were provided in machines as hereto-
fore constructed whereby the pinion could be
raised to compensate for the lift of the cylin-
der. Therefore the lifting of the cylinder-wheel
separates the pitch-lines of these gears and
causes a looseness or backlash between the
surface of the cylinder and the face of the
type-bed, which is an objectionable feature in
a printing-press.

The object of this invention is to obviate by
simple means this backlash and to secure an
accurate relation of motion between the bed
and cylinder.

The means by which we obtain these results
we will now describe with reference to the ac-
companying drawings for a fuller and better
understanding of the same.

Figure 1 shows a fragmentary side elevation 50
of that portion of a printing-press to which
our invention particularly belongs. Fig. 2 is
a sectional elevation of same, showing, in addi-
tion to our invention, its relation to those devices
which are common to all presses of this class. 55
Fig. 3 represents, partly in section, a portion of
Fig. 2 enlarged for the purpose of showing
distinctly that portion of the arrangement
which we claim as new. Fig. 4 shows a sec-
tional plan view of Fig. 3.

Similar letters refer to similar parts through-
out the several views.

In order that we may more clearly explain
our invention, we have shown the several parts
of a printing-press.

A represents the impression-cylinder, which
is caused to revolve uniformly on its axis.

B is the type-bed, which has a reciprocating
motion, and which moves isochronously with
the surface of the cylinder A during the in- 70
terval of printing or on the direct motion of
the bed.

C C are the frames of the machine, wherein
are the longitudinal grooves b b, in which the
bed B is free to slide.

M is a cross-stay, which ties frames C C to-
gether.

L is a slotted bracket, secured to the cross-
stay M, and acts as a support to the oscillat-
ing bearing-block V of the shaft G.

Secured to the cylinder A at its journal k,
and beyond the journal-box d, is the cylinder
gear-wheel E, which meshes into a two-faced
spur-pinion, F, below it, said pinion being se-
cured to the shaft G. By this combination 85
the rotary motion of the cylinder is trans-
mitted to the shaft G, which in turn commu-
nicates a reciprocating motion to the bed B by
the intervention of the well-known “mangle”
movement, which movement requires that the 90
shaft G shall oscillate vertically to a limited
degree while changing the direction of motion
of the bed. This limit is clearly represented
by the dotted position in Fig. 3.

While the cylinder is “down” the shaft G is 95
at its lowest position, as shown in Fig. 2, and is
driving the bed uniformly with the surface of
the cylinder, the motion being communicated

through the shaft G and the reversing-pinion O to the rack-hanger H, which is secured rigidly to the under side of the bed. At either end of this rack-hanger well-known devices are used to cause the shaft G to change its line of rotation from its upper or lower limit, and thereby reverse the direction of motion of the bed. The oscillating motion of this shaft is utilized in any desired manner to give the necessary rise and fall to the axis of the cylinder A.

The shaft G is provided with suitable bearings at its ends, wherein it is free to revolve. Its journal S is supported in the yoke N, which yoke has trunnions I I at its ends, whereby it is supported between the stationary brackets K K, the axis of said yoke lying through the axis of shaft G and parallel to the line of motion of bed. Therefore these trunnions form the center from which the shaft G swings in its vertical oscillations. The journal T of this shaft is supported in a rectangular block, V, which slides vertically in the stationary slotted bracket L, which bracket is so constructed as to support the shock of the bed when its motion is reversed, and at the same time permits a free vertical motion to the shaft G and block V.

By reference to Fig. 3 it will be seen that the two-faced pinion F engages its inclined faces f and f' (which faces are a counterpart of one another) alternately with that of the cylinder-wheel E. The position of parts herein represented is opposite from that shown in Fig. 2, though the dotted position shows the other extreme of motion or that corresponding to Fig. 2.

If the center of oscillation of the shaft G were to be located, as in all machines heretofore constructed, directly in the plane of center of cylinder-wheel's face, as on the line xx , Figs. 2, 3, and 4, the oscillatory motion of the shaft G could have no other effect on the working position of the two-faced pinion F than to present alternately its faces f and f' to the cylinder-wheel E. Therefore the raising of the cylinder would leave an intervening space between the pitch-line of one or the other of the faces of the pinion F and the pitch-line of the cylinder-wheel E, which, as we have hereinbefore stated, would give rise to an objectionable backlash. To prevent this, and with a view to securing a more quiet running mechanism, we

have placed the center of oscillation of the shaft G outside or beyond the center line, xx , as shown at I, Fig. 3, so that while the shaft 55 changes from its upper to its lower limit of oscillation, or vice versa, the pitch-lines of the wheels E and F are kept in perfect working contact. When the cylinder rises the rising of the shaft causes the pinion F to follow up 60 the cylinder-wheel while presenting its opposite face to be operated upon by said cylinder-wheel. The exact location of this center of oscillation is dependent on the rise and fall of the cylinder-axis and the relation of such motion to that of the rise and fall of shaft G. We have preferred to locate this center outside or beyond the two-faced pinion F, though the same result could be obtained by placing the center inside of the pinion F, or between said 70 pinion and the reversing-pinion O, the only difference in the operation being that in this last construction the shaft G would be revolving in its upper limit of oscillation while the cylinder was down, or vice versa.

We are aware that the mechanical devices herein described for driving the bed and cylinder of a printing-press are not new *per se*, and we do not claim broadly a combination of such devices for such purposes; but,

As of our invention, we claim—

In a cylinder printing-press, in combination with a gear-wheel attached to the impression-cylinder, constructed and adapted to be raised and lowered at alternate revolutions, a double-faced pinion mounted on an oscillating and rotary shaft whose point of oscillation lies without a plane equally dividing the face of the gear-wheel, whereby the teeth on each face of said pinion are caused to follow and alternately engage at a constant depth of engagement with the teeth of said gear-wheel in the raised and lowered positions of the cylinder in the operation of printing a sheet, substantially as set forth.
